MUSICAL INSTRUMENT

Lyle M. Hartman, Okotoks, Alberta, Canada

Application March 4, 1949, Serial No. 79,611

5 Claims. (Cl. 84—313)

1

My invention relates to new and useful improvements in musical instruments, more particularly to instruments wherein the sound is produced by the striking of wires under tension with hammers or the like, operated by piano-type keys, an object of my invention being to provide a device of the character herewithin described which has the playing technique of a piano but due to the novel construction including the sound box produces a distinctive tone.

Another object of my invention is to provide a device of the character herewithin described which incorporates means whereby a tremolo effect may be produced by the manipulation of the piano-type keys.

A further object of my invention is to provide a device of the character herewithin described which is portable and which may be supported either upon a table or upon folding legs provided with the instrument.

A still further object of my invention is to provide a device of the character herewithin described which although being portable has a musical range of at least four octaves.

Another object of my invention is to provide a device of the character herewithin described which is relatively economical in manufacture and which provides a useful and pleasing addition to the variety of instruments now being manufactured.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which—

Figure 1 is a top plan view of my device.

Figure 2 is a side elevation of Figure 1 with the legs extended.

Figure 3 is an enlarged perspective fragmentation of my playing assembly sectioned in part to show the details thereof.

Figure 4 is an enlarged fragmentary detail of one of my hammer assemblies in the normal or non-playing position.

Figure 5 is an enlarged fragmentary drawing of one of my hammer assemblies, with the key in the down or striking position.

In the drawings like characters of reference indicate corresponding parts in the different figures.

Proceeding to describe my invention in detail, it will be seen upon reference to the accompany-

2

ing drawings that the musical instrument embodies the casing 1 having a substantially harpiform configuration when viewed in plan and supported by the folding legs 2 pivotally attached to the underside thereof and braced by means of the diagonal struts 3. The casing 1 comprises the upper and lower panels 4 held in spaced relationship by means of the side pieces 5, thus forming the sound box 6, the purpose of which 10 will hereinafter be explained.

Surmounting the forward end 7 of the casing is my keyboard assembly collectively designated 8, of substantially harpiform configuration comprising the front anchor plate 9 spanning two 15 keyboard endplates 10 between which a set of black and white piano-type keys 11 are situated. Strings 12 span the upper panel 4 of the casing 1 extending from the forward face 13 to which they are attached by means of screws or the like, 20 to the conventional pitch adjusting keys 14 situated adjacent the rearmost edge 15 of the casting. The strings are elevated from the upper face by means of the front bridge 16 situated parallel with the aforementioned forward edge 13, and the rear bridge 17 situated adjacent to and parallel with the aforementioned rear edge 15.

Figure 3 of the accompanying drawings shows the arrangement of the keyboard assembly 8 and 30 it will be seen that the keys 11 are pivotally attached within the recess 18 formed on the underside of the key supporting member 19 which spans the end plates 10 as clearly shown in Figure 1. The keys 11 are drilled transversely towards 35 rear end 20 thereof and are rotatably mounted upon a shaft 21 also extending between the end plates 10. A longitudinally extending strip of felt or the like 22 is attached to the forward under-surface of the recess 18 against which the 40 upper surface of the keys bear in order to eliminate any undesirable noise when the key returns to the raised position. A rectangular recess 23 is provided in the under side of the key slightly forward of the centre thereof within 45 which is receivable the bifurcated attachment arm 24 pivotally attached at one end thereof to the key by means of the pin 25 extending transversely across the recess.

Striking actions collectively designated 26 comprise the connecting rod 27, bell cranks 28 and the return springs 29. Bell cranks 28 are journaled for rotation upon a shaft 30 which is supported by the extension 31 of the U-shaped members 32 attached to the internal face of 55 the front anchor plate 9 by means of bolts 33.

These U-shaped members are adjacently situated across the width of the anchor plate 9, alternate members having the aforementioned extensions 34 in order to support the shaft 30. Each U-shaped member is designed in this embodiment to contain the actions for three consecutive keys and is provided with the spring carrying anchor plate 34 held in position by the aforementioned bolts 33, vertical adjustment thereof being permitted by the vertical slotting of the attaching apertures 35 for the purpose hereinafter to be explained.

The spring anchor plates 34 are provided with the upper flange 36 upon which is attached the felt stripping 37 which acts as a cushion for the forward underside edges 37' of the keys 11 when same are depressed. The lower flanges 38 of the anchor plates extend outwardly and upwardly from the attaching portion substantially as shown in Figure 4 of the accompanying drawings, and are provided with apertures 39 adjacent to the edges thereof into which are receivable the ends of the striking action return springs 29. The return springs extend between the anchor plates 34 and the upper arm 40 of the bell crank component 28. The connecting rods 27 of the striking action extend between the lower arms 41 of the bell crank components to which they are pivotally attached by means of pins 42 and the distal ends of the aforementioned attachment arms 24. In this embodiment the upper end of the connecting rod 27 acts as a ball receivable within the two socket portions 43 on the end of the arm 24, the tension thereof being controlled by means of setscrews 44 in the conventional manner.

The hammers collectively designated 45 comprise flat resilient strips of material 46 secured by means of setscrews or the like to the underside of bell cranks 28 within a slotted shoulder 47. The resilient strip 46 is stiffened at the point of attachment to the bell crank by a reinforcing leaf spring 48 also receivable within the shoulder 47 as clearly shown in Figure 4 of the accompanying drawings. A string impacting hammer head 49 is provided upon the distal end of the resilient strip 45 being felt covered in the conventional manner.

A novel feature of my piano-harp is the vibrating assembly collectively designated 50 by which I obtain a tremolo effect in playing. This assembly comprises a flat resilient strip of material 51 attached to the underside of the aforementioned anchoring bracket 34 by means of setscrews or the like being stiffened by a leaf spring 52 as clearly shown in Figure 4. A stationary intercepting promontory 53 in the form of a relatively small wheel is provided on the underside of the distal end of the flat strip 51 and is engageable by the butt-end extension 54 of the hammer 46 which extends rearwardly from the slotted shoulder 47 of the bell crank 28. In the embodiment illustrated, the butt end extension is shown as a separate strip of material which has the effect of further stiffening the hammer but it will be appreciated that it may if desired be formed with the hammer 46. The aforementioned promontory 53 is engageable by the extension 54 when the hammer is in the depressed or striking position, the strip 51 carrying the promontory 53 being flexed with and by the extension 54 thus placing the hammer 46 under tension which permits rapid oscillation of the key thus providing a tremolo effect as will hereinafter become apparent.

I have provided a string damper 55 upon the distal end of the butt end extension 54 which engages with the string when the hammer is released thus eliminating the vibration of the string after the note has been struck.

In operation the key 11 is depressed or struck journaling around the key shaft 24 and causing the connecting rod 27 to rotate the bell crank 28 thus placing the return spring 29 under tension. The bell crank in rotation moves hammer 45 in an arc causing the hammer head 49 to strike the string 12 thus producing the note. It should be observed that the stationary promontory 53 intercepts the butt end extension 54 just prior to the hammer head 49 striking the string thus placing the hammer under spring tension which permits the aforementioned tremolo effect to be produced by the oscillation of the key. The forward undersurface edges 37' of the keys should be adjusted with relation to the felt stripping 37 by means of the aforementioned slotted portion 35 of the anchor plate 34 in order to ensure that the hammer head 49 strikes the strings before the key meets the felt.

If it is desired to prolong the note then the key is not released entirely as it will be appreciated that upon release of the key the string damper 55 on the end of the butt end extension 54 engages with the string thus stopping the vibration thereof.

As hereinbefore described, a note may also be held by the tremolo method depending upon the kind of music being played or the effects desired by the player.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. A piano-harp characterized by the combination with a horizontally disposed and substantially harpiform keyboard of a set of keys and an associated line-up of shaft-supported hammers therebeneath, a striking action connected to and extending between each key and one of the hammers, said action embodying a bell-crank component journalled on said shaft and a connecting rod extending between said crank and said key, spring means also extending between said crank and an adjacent point of anchorage, said hammers each consisting of a flat resilient strip of material secured to said crank, a string impacting head on the distal end thereof and at least one leaf spring overlying said hammer in the region of attachment of said hammer to said crank for stiffening said strip, and a vibrating assembly composed of a stationary intercepting promontory and a butt-end extension on said hammer engageable with said promontory when said hammer is depressed to produce a vibrating sound effect on said keyboard.

2. A piano-harp characterized by the combination with a horizontally disposed and substantially harpiform keyboard of a set of keys and an associated line-up of shaft-supported hammers therebeneath, a striking action connected to and extending between each key and one of the hammers, said action embodying a bell-crank component journalled on said shaft and a connecting rod extending between said crank

and said key, spring means also extending between said crank and an adjacent point of anchorage, said hammers each consisting of a flat resilient strip of material secured to said crank, a string impacting head on the distal end thereof, and means for vibrating said hammer against the strings of said keyboard when a key is struck.

3. A piano-harp characterized by the combination with a horizontally disposed and substantially harpiform keyboard of a set of keys and an associated line-up of shaft-supported hammers therebeneath, a striking action connected to and extending between each key and one of said hammers, said action embodying a bell-crank component journalled on said shaft and a connecting rod extending between said crank and said key, spring means also extending between said crank and an adjacent point of anchorage, said hammers each consisting of a flat resilient strip of material secured to said crank, a string impacting head on the distal end thereof and at least one leaf spring overlying said hammer in the region of attachment of said hammer to said crank for stiffening said strip, a vibrating assembly composed of stationary intercepting promontory and a butt-end extension on said hammer engageable with said promontory when said hammer is depressed to produce a vibrating sound effect on said keyboard, and a string damper on said extension for engagement with the associated string of said keyboard when said key is released.

4. A piano-harp characterized by the combination with a horizontally disposed and substantial harpiform keyboard of a set of keys and an associated line-up of shaft-supported hammers therebeneath, a striking action connected to and extending between each key and one of said hammers, said action embodying a bellcrank component journalled on said shaft and a connecting rod extending between said crank and said key, spring means also extending between said crank and an adjacent point of anchorage, said hammers each consisting of a flat resilient strip of material secured to said crank, a string impacting head on the distal ends thereof and at least one leaf spring overlying said hammer in the region of attachment of said hammer to said crank for stiffening said

50

strip, and a vibrating assembly composed of stationary intercepting promontory and a butt-end extension on said hammer engageable with said promontory when said hammer is depressed to produce a vibrating sound effect on said keyboard, said extension taking the form of a resilient strip which contacts said promontory before said impacting head makes contact with the string of said keyboard.

5. A piano-harp characterized by the combination with a horizontally disposed and substantial harpiform keyboard of a set of keys and an associated line-up of shaft-supported hammers therebeneath, a striking action connected to and extending between each key and one of said hammers, said action embodying a bellcrank component journalled on said shaft and a connecting rod extending between said crank and said key, spring means also extending between said crank and an adjacent point of anchorage, said hammers each consisting of a flat resilient strip of material secured to said crank, a string impacting head on the distal end thereof and at least one leaf spring overlying said hammer in the region of attachment of said hammer to said crank for stiffening said strip, and a vibrating assembly composed of stationary intercepting promontory and a butt-end extension on said hammer engageable with said promontory when said hammer is depressed to produce a vibrating sound effect on said keyboard, said extension taking the form of a resilient strip which connects said promontory before said impacting head makes contact with the string of said keyboard, and a string damper on said extension for engagement with the string of said keyboard when said key is released.

LYLE M. HARTMAN.
